DESIGN FOR AN ELECTRON DISCHARGE DEVICE

Paul Georges Chevigny, New York, N. Y., assignor
to Federal Telephone and Radio Corporation,
Newark, N. J., a corporation of Delaware

Application June 24, 1943, Serial No. 110,515

Term of patent 14 years

(Cl. D26—8)

To all whom it may concern:

Be it known that I, Paul Georges Chevigny, a citizen of France, residing at New York, in the county of New York and State of New York, United States of America, have invented a new, original, and ornamental Design for Electron Discharge Devices, of which the following is a specification, reference being had to the accompany drawing, forming part thereof.

The figure is a perspective view of an electron discharge device, showing my new design.

The side of the electron discharge device not shown is the same as that illustrated.

I claim:

The ornamental design for an electron discharge device, as shown and described.

PAUL GEORGES CHEVIGNY.
